(57) **CLAIM**

The ornamental design for a display panel with animated graphical user interface, as shown.

DESCRIPTION

FIG. 1 is a first front view of a first embodiment showing an display panel with animated graphical user interface design; FIG. 2 is a second front view of a first embodiment showing an display panel with animated graphical user interface design;

FIG. 3 is a third front view of a first embodiment showing an display panel with animated graphical user interface design;

FIG. 4 is a fourth front view of a first embodiment showing an display panel with animated graphical user interface design;

FIG. 5 is a fifth front view of a first embodiment showing an display panel with animated graphical user interface design; FIG. 6 is a sixth front view of a first embodiment showing an display panel with animated graphical user interface design;

FIG. 7 is a seventh front view of a first embodiment showing an display panel with animated graphical user interface design;

FIG. 8 is a first front view of a second embodiment showing an display panel with animated graphical user interface design;

FIG. 9 is a second front view of a second embodiment showing an display panel with animated graphical user interface design;

FIG. 10 is a third front view of a second embodiment showing an display panel with animated graphical user interface design;

FIG. 11 is a fourth front view of a second embodiment showing an display panel with animated graphical user interface design;

FIG. 12 is a fifth front view of a second embodiment showing an display panel with animated graphical user interface design;

(Continued)

FIG. 13 is a sixth front view of a second embodiment showing an display panel with animated graphical user interface design; and,

FIG. 14 is a seventh front view of a second embodiment showing an display panel with animated graphical user interface design.

The portions of the display panel with animated graphical user interface shown in broken lines illustrate portions of the display panel with animated graphical user interface that form no part of the claimed design.

1 Claim, 6 Drawing Sheets
